UNITED STATES PATENT OFFICE.

ROBERT J. NIGHTINGALE, OF EAST CLEVELAND, OHIO, ASSIGNOR TO WILLARD STORAGE BATTERY COMPANY, OF CLEVELAND, OHIO, A CORPORATION OF WEST VIRGINIA.

TERMINAL CLAMP FOR STORAGE BATTERIES.

Application filed April 10, 1922. Serial No. 551,084.

This invention relates to a terminal clamp for storage batteries, and has for its chief object to provide a clamp by which good electrical connection may be made between a conductor and the terminal post of a battery, with a clamp which may be produced inexpensively. More particularly, it is the aim of the invention to provide an efficient clamp made from sheet metal. Still further the invention aims to provide a sheet metal clamp adapted particularly for small batteries such as a radio battery.

The invention may be briefly summarized as consisting in certain novel details of construction, and combinations and arrangements of parts which will be described in the specification and pointed out in the appended claims.

In the accompanying sheet of drawings, Fig. 1 is a side view of my improved clamp applied to a terminal post and conductor; Fig. 2 is a plan view of the same; Fig. 3 is a sectional view along the line 3—3 of Fig. 1; Fig. 4 is a section along the line 4—4 of Fig. 2; and Fig. 5 is a section along the line 5—5 of Fig. 3.

Referring now to the drawings, 10 represents the terminal post of a storage battery, 11 my improved terminal clamp, and 12 a flexible conductor which is electrically connected to the terminal post by the clamp, the conductor being connected to the clamp and the clamp to the post in the manner herein-after explained.

The clamp 11 is preferably formed from sheet metal having a certain degree of spring or elasticity such as sheet steel, brass, phosphor bronze or other suitable sheet metal, and in practice the clamp is preferably lead coated to prevent corrosion.

The clamp is provided with a socket portion 13, which is formed by bending a portion of the stamping from which the clamp is made into substantially annular form, and additionally the clamp is provided with end portions 14 and 15 which project in substantial parallelism from the body or socket portion 13. The socket portion 13 is generally tapered though it may be cylindrical. If the top of the post 10 is tapered, as is usually the case, the socket portion 13 is tapered, but if the clamp is to be fitted onto a cylindrical post the socket portion will be cylindrical.

The two end portions 14 and 15 have

aligned openings 14^a and 15^a to accommodate a transverse clamping screw 16, which in this instance performs the double function of drawing together the end portions 14 and 15 so as to tightly clamp the socket portion of the clamp on the terminal post 10 and of securing the end of the conductor 12 to the clamp. In this instance an ordinary screw is employed and the hole 15^a is threaded, but this is not essential as a small bolt with a thumb nut may be employed, in which event neither hole need be threaded. Preferably the metal surrounding the hole 14^a in the portion 14 of the clamp is countersunk as shown at 14^b to accommodate the head of the screw.

In order that the end portions 14 and 15 may be properly drawn together by the screw 16 to secure the clamp to the post they are provided outwardly beyond the screw with abutting portions and in this instance the part 14 is bent or offset inwardly to substantially the center line of the clamp as shown at 14^c, and the part 15 has an inwardly turned lip 15^b adapted to bear against the offset portion of the part 14.

The free end or offset part 14^c of 14 projects outwardly beyond the lip 15^b of 15, and this offset part 14^c is provided with ears 14^d adapted to be bent around or over the insulated part of the conductor 12. In practice the insulating part of the conductor rests upon the offset portion 14^c of the part 14 and the free or bare end of the conductor is extended inwardly and is clamped beneath the head of the screw 16 as shown in the drawings. If desired, the head of the screw may be undercut, forming an annular shoulder adapted to bear solidly against the conductor resting on the countersunk seat 14^e. With this arrangement, inasmuch as the insulated portion of the conductor rests upon the depressed or offset portion of the part 14, the bare part of the conductor is substantially on a line with the seat 14^e against which it is designed to be clamped by the screw. Preferably there is an inclined depression or groove 14^f provided at the shoulder where the offset portion 14^c joins the main portion 14, this groove leading to the countersunk seat and forming in effect a guideway for the end of the conductor.

Thus it will be seen that with one screw the clamp is secured to the post, and the end

of the conductor is secured to the clamp, and with this single screw a very good electrical connection is made between the conductor and post. At the same time, the clamp being 5 in the form of a stamping, can be produced inexpensively, and is adapted for quantity production.

Having described my invention, I claim:

In combination, a storage battery terminal 10 post, a clamp having a socket portion adapted to encircle the post and having substantially parallel outstanding end portions, a fastening device extending transversely through said outstanding portions, one of

said outstanding portions having its end bent 15 inwardly to form an abutment and the other outstanding portion having an inwardly offset extension adapted to engage the abutment and projecting beyond the abutment, said extension being formed to embrace a conductor, and a conductor having an insulated portion received in said extension, said conductor being secured to the clamp under the fastening device.

In testimony whereof, I hereunto affix my 25 signature.

ROBERT J. NIGHTINGALE.
